S. Sawyer,
Making Hoops.
No 16,513. Patented Jan. 27, 1857.

UNITED STATES PATENT OFFICE.

SYLVESTER SAWYER, OF FITCHBURG, MASSACHUSETTS, ASSIGNOR TO AMERICAN HOOP MACHINE COMPANY.

MACHINE FOR PLANING HOOPS.

Specification of Letters Patent No. 16,513, dated January 27, 1857.

To all whom it may concern:

Be it known that I, SYLVESTER SAWYER, of Fitchburg, in the county of Worcester and State of Massachusetts, have invented certain new and useful Improvements in Machines for Shaving Hoops, of which the following is a full, clear, and exact description, reference being had to the annexed drawings, making part of this specification, in which—

Figure 1, is a plan. Fig. 2, an elevation. Fig. 3, a horizontal section upon the line A, A, of Fig. 2. Fig. 4, details of the cutters and rest.

15 My present invention consists in certain improvements upon a machine for which Letters Patent were granted to myself in connection with Joseph Sawyer for improved hoop machine on the sixth day of 20 May 1856.

To enable others skilled in the art to understand my invention, I will proceed to describe the manner in which I have carried it out.

25 The machine is set in motion by power applied to the pulley A, upon the driving shaft B. To the fly wheel C, upon this shaft is attached a crank pin a , (seen dotted in Fig. 2) from which by the pitman D, a vertically reciprocating motion is communicated to the gate E which slides upon the standard G, and is guided by suitable straps f. The bar E, carries the cutters b, and c, the former being set rank to reduce the hoop to a uniform thickness, the latter which is the longest finishing the surface. They are also so arranged that the cutter b, shall operate upon the down stroke, and the cutter c, upon the up stroke. Immediately behind the 30 cutter is the rest H, against which the finished surface of the hoop rests, the roll I, serving to hold it up to the rest and cutters as will be hereafter explained.

40 The hoop enters the machine between the rolls K, and L, heretofore one of these rolls has been stationary the other being hung with springs and allowed to yield sufficient to permit the passage of a knot. By thus throwing all the motion into one of the rolls, 45 the hoop was liable to be bent out of its general line of motion, and to be shaved unevenly.

K is the movable roll which is forced up to its work by the spring M, the strength of this spring is adjusted by the screw g . The 55 roll L, is hung in the frame N which is pivoted upon the shaft X and has attached to it a lever O, the position of which is regulated by the screw n , to accommodate the position of the roll to the general size of the 60 hoops to be shaved. To allow for the yielding of the roll L upon the passage of a knot, a slight play is allowed to the lever O, between the set screws m , and n , and it is held against the latter by a spring P, which 65 is of a strength that will allow it to yield after the spring M, is slightly compressed. For the slight inequalities of the hoop the roll K, will yield, but upon the arrival of a knot opposite to the roll L, the spring P 70 yields to permit its passage, and thus the hoop is prevented from being thrown so far to one side as would otherwise be the case were the roll L, rigid and immovable. This device is necessary only when 75 knotty stuff is operated upon, where the hoops are clear of knots, or when the knots are trimmed close, the lever O, and roll L, 80 may be held stationary by the set screws m and n .

The roll I, is hung in the frame P', and is kept up to its work by the spring Q. The motion of the frame P', in one direction is limited by the eccentric R, the position of which is regulated by the lever S, and graduated arc T, by means of which the distance of the roll I from the cutters is adjusted for any desired thickness of hoop, and the operator is enabled gradually to bring up this roll as the end of the hoop passes through 85 to form the lap.

The worm V, gives motion to the gear W, upon the shaft X, and a gear Z upon this shaft engages with a similar gear Y, upon the shaft V, of the roll L, by which means 90 this roll is driven.

What I claim as my invention and desire to secure by Letters Patent, is—

1. Giving the frame N, which carries the roll L, a play between the adjusting screws 100 m , and n , and bringing the roll up to its work by the spring P, in the manner and for the purpose set forth.
2. I claim the eccentric R, lever S, grad-

uated arc T, and spring Q, operating in the manner described for the purpose of regulating the thickness of the hoop and of forming the lap as set forth.

5 3. I claim the combination of the cutters b, and c, arranged in the manner set forth upon the reciprocating gate E in combina-

tion with the rest H operating in the manner substantially as set forth.

SYLVESTER SAWYER.
